UNITED STATES PATENT OFFICE.

GEORGE H. GILMAN, OF BELMONT, MASSACHUSETTS.

DRILLING MACHINE.

Application filed January 6, 1923. Serial No. 611,173.

My invention relates to drilling machines and particularly but not exclusively to hammer rock drills operated by compressed air.

My invention will be best understood from the following description when read in the light of the accompanying drawings of one specific embodiment of my invention submitted for illustrative purposes, while the scope of my invention will be more particularly pointed out in the appended claims.

In the drawings:

Fig. 1 shows a longitudinal section of a hammer rock drill;

Fig. 2 is a section of the rearward end of the rock drill on the line 2—2 of Fig. 1;

Fig. 3 is a section on the line 3—3 of Fig. 1; and

Figs. 4, 5, 6 and 7 respectively are sections on the lines 4—4, 5—5, 6—6 and 7—7 of Fig. 2.

Referring to the drawings the drilling tool is exemplified by the drill steel 1, the shank 3 of which is carried by the chuck 5 in such manner that the drill steel must rotate with the chuck. Rearwardly of the drill steel I mount a reciprocating piston, the same as shown being provided with a head 7, forward extension 9, and rearward extension 11, the latter being reduced in diameter at 13 adjacent its juncture with the head.

As illustrated the casing for the rock drill includes a section 15 which has a bore 17 in which the chuck is rotatively mounted and which receives the forward extension 9 of the piston. The casing section 19 located rearwardly of and abutting the section 15 has a bore 21 receiving the head 7 of the piston, and a bore 23 receiving the forward extension 9 of the piston. Abutting the rearward side of the section 19 is a casing section 25 which has a bore 27 in which is permanently secured the casing section 29, the latter being provided with the bore 31 which receives the rearward extension 11 of the piston. The rearward face of the casing section 25 is recessed to receive the exterior flange 32 of the section 29. Rearwardly of the flange the section 29 is reduced in diameter at 33 and rearwardly of the reduced diameter portion 33 it is further reduced in diameter at 35 to provide the shoulder 37.

For supplying motive fluid for operating the piston, the exterior of the portion of the casing section 29 received in the bore 27 of the casing section 25 is shown as provided with annular grooves 39 and 41, the former

of which as shown by Fig. 2 is adapted to be placed in communication with a source of motive fluid supply by way of the passage 43 leading from the throttle valve 45, while the groove 41 as shown by Fig. 1 is placed in communication with the forward end of the bore 21 by means of passages 47. Further for placing the annular groove 39 in communication with the bore 31 is shown a pair of diametrically opposite radial passages 49 shown in Fig. 1, and leading rearwardly through the wall of the casing section 29 as shown by Figs. 1, 4 and 6 are two groups of longitudinal passages 51 which at their forward ends intersect the radial passages 49 and at their rearward ends are placed in communication with the bore 31 by means of an intersecting annular groove 53 formed as an enlargement of said bore. Intersecting each group of passages 51 and the corresponding radial passage 49 are shown short slots 55 formed in the wall of the bore 31. As shown best by Fig. 2 in the same plane as the slots 55 is a pair of diametrically opposite radial passages 57 which connect the bore 31 with the annular groove 41.

For exhausting the motive fluid which operates the piston I herein form in the intermediate portion of the bore 21, as shown by Fig. 1, a pocket 59 which is placed in communication with the exhaust nozzle 61 of the machine by means of passages 63.

In the operation of the machine when the throttle valve 45 places the passage 43 in communication with a source of motive fluid supply, motive fluid enters the groove 39 and passes to the rearward end of the cylinder by way of the grooves 55, passages 51 and groove 53, and in consequence of this motive fluid continuously acts upon the rearward end of the extension 11 of the piston. In the position of parts as shown in Figs. 1 and 2 of the drawings motive fluid will pass from the bore 31 into the groove 41 by way of the radial passages 57, and thence to the forward end of the bore 21 by way of the passages 47, the grooves 55 at this time acting to supply additional motive fluid to the bore 31. In consequence of this the piston will make its rearward stroke, the motive fluid then at the rearward end of the bore 21 exhausting to the atmosphere by way of the pocket 59, passages 63 and exhaust nozzle 61. When the piston moves rearwardly far enough to bring the reduced portion 13 of the extension 11 into communication with

the radial passages 49 motive fluid flows from the latter into the rearward end of the bore 21. In consequence the piston moves forwardly due to the pressure on the rearward face of the head 7 and rearward end of the extension 11, the motive fluid in front of the head 7 exhausting to the atmosphere by way of the pocket 59.

As the particular details of the hammer 10 piston and the way in which it is reciprocated do not form part of my present invention the same will not be further described.

I will now describe the present illustrative embodiment of the mechanism and associated parts provided for rotating the chuck.

On the reduced diameter portion 35 of the casing section 29 is mounted the sleeve-like casing section 65 which at its forward end has a flange 67 abutting the shoulder 37 of the casing section 29. Formed in the outer surface of the section 65 is an annular groove 69 closed by the adjacent surface of the section 71 which surrounds and is permanently secured to the section 65. Between the casing sections 71 and 25 are the casing sections 73 and 75 which surround the reduced diameter portion 33 of the casing section 29.

The casing section 73 just referred to, as best shown by Fig. 4, is provided with a central recess 77 and the side recesses 79 intersecting the central recess. The recess 77 houses a spur gear 83 which is mounted for rotation upon the reduced diameter portion 33 of the casing section 29, and in each of the recesses 79 is a gear 85 in mesh with the gear 83. The gears 85 are removably keyed to shafts 87 which extend forwardly through the casing to the rearward end of the chuck. At their forward ends the shafts 87 each carry a pair of oppositely disposed eccentrics 89 formed integrally with the shafts and upon opposite eccentrics are mounted the yokes 91. Each yoke 91 is provided with internal gear teeth 93 which mesh with external gear teeth 25 upon the chuck. By this construction it will be noticed that when the shafts rotate they must rotate in unison, which will cause the yokes to be gyrated on an orbit the diameter of which is twice the eccentricity of the eccentrics 89, and that this will cause the chuck to be rotated at a much slower speed than the shafts.

For rotating the shafts I employ fluid pressure actuated motor mechanism. Herein to this end as shown by Figs. 1, 2 and 6 the casing section 75 is recessed at opposite sides to form in conjunction with the reduced diameter portion 33 of the section 29 a pair of annular chambers 97, the inner wall of which is the reduced diameter portion 33 of the casing section 29 and the outer wall of which is the peripheral portion of

the casing section 75, the chambers being separated by the diaphragm 98 formed by recessing the casing section 75.

Each annular chamber 97 is shown divided into two chambers 99 and 101 by 70 means of an annular yoke 103 which surrounds the reduced diameter portion 33 of the casing section 29. The chambers 99 and 101 may be rendered alternately expandable and contractable when the yoke 103 moves 75 by any suitable means cooperating with the walls of the casing. Herein I have shown the outer chambers 99 so rendered, the same being each sub-divided into two chambers by means of the vanes 105, each vane having a cylindrical head 107 mounted for oscillation at the ends of the major axes of the members 103, and the opposite ends of the vanes being received in slots 108 of the plugs 109 mounted for oscillation in the casing sections 75 and adjacent portions of the casing sections 25 and 73. As clearly illustrated in Fig. 1 the vanes 105 and members 103 laterally fit the diaphragm 98 and walls of the chambers 97 opposite the diaphragm in a 80 fluid tight manner. The members 103 are mounted upon eccentrics 111 formed integrally with the shafts 87, the shafts between the eccentrics being provided with integral disk like portions 113 of larger diameter 85 than the eccentrics and rotating the cylindrical openings 115 formed in the diaphragm 98 coaxially with the shafts. It will be understood by this construction that if the members 103 are caused to gyrate the 90 chuck will be driven through the reduction gear at the forward end of the shafts. The gyration of the members 103 I cause by admitting and exhausting motive fluid to and from the expandable chambers and for the purpose of increasing the power of the arrangement I preferably make the eccentrics 111 of greater eccentricity than the eccentrics 89. For controlling the motive fluid admitted to and exhausted from the expandable chambers I provide a rotary valve 117 which is keyed to a gear 119 shown in Figs. 2 and 4 meshing with the gear 83 and which is of the same pitch diameter as the gears 85 so that the valve will rotate in unison 105 with the shafts 87.

As shown in Fig. 1 the valve 117 herein is in the form of a tube separated into two portions by means of the diaphragm 121. The forward end of the tube is placed in communication with the motive fluid supply by way of the passage 123 leading to the throttle valve 47, while the rearward end of the valve is placed in communication with the atmosphere by way of a passage 125, shown in Figs. 2 and 7, leading to the exhaust nozzle 61.

As shown in Figs. 2, 5 and 6 the interior of the tubular valve 117 upon opposite sides of the diaphragm 121 is placed in commu- 130

nication with the exterior of the valve by means of slots 127 and 129. Referring to Fig. 5 it will be noticed that in the plane of the slot 127 the casing section 75 has formed 5 therein a passage 131 leading radially through the diaphragm 98 and communicating with the semi-annular groove 133 formed in that surface of the diaphragm in contact with the reduced diameter portion 33 of the 10 casing section 29, and that leading from the annular groove 33 toward the bottom of the casing is a passage 135. The passage 131 is placed in communication with the expansible chamber at the upper side of the rearward member 103 by way of the port 137, 15 shown in Figs. 2 and 5, while the passage 135 is placed in communication with the expansible chamber at the lower side of the forward member 103 by way of a similar passage 139 20 as indicated by Fig. 5. From this it will be seen that as the valve rotates motive fluid will be intermittently supplied to the passage 131 by way of the slot 127 of the valve, and that this will intermittently supply motive fluid to the expansible chamber at the upper side of the rearward member 103 and to the expansible chamber at the lower side of the forward member 103. Again referring to Fig. 5 it will be seen that formed in 25 the casing section 75 is also a passage 141 which intersects the bore receiving the valve 117 in the plane of the slot 127 opposite the point of intersection of the passage 131 with said bore. The passage 141 has in communication therewith a passage 143 leading to a semi-annular groove 145, the latter formed in a similar manner to the semi-annular groove 133, and leading from the groove 145 30 is a passage 147. The passage 143 opens into the expansible chamber at the upper side of the forward member 103 by way of a port 147, while the passage 147 is placed in communication with the expansible chamber at the lower side of the rearward member 103 35 by way of a port 149. It will be noticed by the above described construction that the slot 127 is alternately placed in communication with the passages 131 and 141 so that when the expansible chamber at the lower side of one member 103 is supplied with motive fluid the expansible chamber at the upper side of the other member 103 will be supplied with motive fluid, and vice versa.

As clearly shown by Fig. 5 the semi-annular groove 133 has opening into it a passage 151 with which communicates a passage 153. The passage 153 in the plane of the slot 129 of the valve as shown by Fig. 6 opens into the bore receiving said valve by way of a 40 port 155. Opposite the port 155 is a port 157 which leads by way of the passage 159 to the passage 143. As heretofore indicated the groove 133 and passage 143 are in communication with expansible chambers at opposite sides of the members 103, and conse-

quently as the valve rotates the opposite sides of these members will be alternately placed in communication with the atmosphere by the slot 129. The ports and passages of course are so timed as to cause the 70 expansible chambers at one side of each member 103 to be exhausted when the chambers at the opposite side are supplied with motive fluid.

For venting the leakage to the chamber 75 101 I place in communication therewith a passage 161 which opens into the annular groove 69 as shown in Fig. 2. The annular groove 69 is placed in communication with the passage 125 by way of the passage 163, 80 as clearly shown in Figs. 2 and 7.

For holding the parts in assembled relation I have shown the four side bolts 165 which extend from one end of the machine to the other. For permitting the section 25 85 to be removed together with the motor without disassembling the latter I form in the reduced diameter portion 35 of the casing section member 29 a socket 167 into which is screwed a plug 169 having a flange 171 engaging the rearward faces of the casing sections 65 and 69. Further for this purpose each shaft 87 is made in two sections, the rearward section 173 which carries the gears 85 and eccentrics 107 having an end 175 of 90 square cross-section which is detachably received in the socket 177 of similar cross-section formed in the end of the forward section 179 of the shaft.

Although I have described for purposes 100 of illustration one specific embodiment of my invention it is to be understood that within the scope of my invention wide deviations may be made therefrom without departing from the spirit of my invention. 105

Claims—

1. In a rock drill, a chuck formed for carrying a drill steel, a hammer piston for operating said drill steel, a casing for said chuck and hammer piston, a pair of rotatably mounted shafts positioned at opposite sides of said casing and extending from the forward to the rearward end of said casing, a pair of eccentrics adjacent each end of each shaft, a pair of yokes at the forward end of said casing, a pair of yokes at the rearward end of said casing, said yokes at the forward end having internal gear teeth meshed with external gear teeth on said chuck, all of said yokes being mounted 110 upon said eccentrics, means for causing said shafts to rotate in unison, and means permitting motive fluid to act upon said yokes at the rearward end of said casing for causing said shafts to rotate.

2. In a rock drill, a chuck, a casing, a gyratory yoke at the forward end of said casing, a gyratory yoke at the rearward end of said casing, means enforcing conjoint movement of said yokes, a piston having 125

forward and rearward extensions of reduced diameter reciprocating in said casing through said yokes, the yoke at the forward end of said casing surrounding said chuck and being geared thereto, and means for permitting motive fluid to act upon the exterior of said yoke at the rearward end of said casing for causing said conjoint movement of said yokes.

3. In a rock drill, a chuck, a casing, a gyratory yoke at the forward end of said casing, a gyratory yoke at the rearward end of said casing, means enforcing conjoint movement of said yokes, a piston having a rearward extension of reduced diameter reciprocating in said casing through said yoke at the rearward end of said casing, the yoke at the forward end of said casing surrounding said chuck and being geared thereto, and means for permitting motive fluid to act upon the exterior of said yoke at the rearward end of said casing for causing said conjoint movement of said yokes.

4. In a rock drill, a piston having a rearward extension of reduced diameter, a chuck formed for carrying a drill steel operated by said piston, a casing for said chuck and piston, the portion of said casing receiving said extension of said piston being exteriorly reduced, a gyratory member surrounding said portion of said casing, means for permitting motive fluid to act upon the exterior of said gyratory member for operating it, and reduction gearing for transmitting motion of said gyratory member to said chuck.

5. In a rock drill, a piston having a rearward extension of reduced diameter, a chuck formed for carrying a drill steel operated by said piston, a casing for said chuck and piston, the portion of said casing receiving said extension of said piston being exteriorly reduced, a pair of gyratory members surrounding said portion of said casing, means for permitting motive fluid to act upon said gyratory members for operating them, and reduction gearing for transmitting the motion of said gyratory members to said chuck.

6. In a rock drill, a piston having a rearward extension of reduced diameter, a chuck formed for carrying a drill steel operated by said piston, a casing for said chuck and piston, the portion of said casing receiving said extension of said piston being exteriorly reduced, a pair of members surrounding said portion of said casing and mounted for simultaneous gyration in out of phase relation, means for permitting motive fluid to act upon said gyratory members for operating them, and reduction gearing for transmitting the motion of said gyratory members to said chuck.

7. In a rock drill, a piston having a rearward extension of reduced diameter, a chuck formed for carrying a drill steel operated

by said piston, a casing receiving said chuck and piston, said casing providing a wall with a bore for said rearward extension and a pair of annular chambers about said wall, gyratory members in said chambers, said gyratory members surrounding said wall and dividing said chambers each into a pair of sub-chambers, means associated with said casing and gyratory members for rendering one of said sub-chambers of each pair alternately expandible and contractable when said gyratory members operate, means permitting motive fluid to be admitted and exhausted to and from said sub-chambers so rendered for causing gyration of said members, and means for causing said gyrations to rotate said chuck.

8. In a drilling machine, a chuck having external gear teeth, a gyratory member surrounding said chuck and having internal gear teeth meshing with the gear teeth on said chuck, a second gyratory member mounted rearwardly of said chuck, means enforcing conjoint movement of said gyratory members, and means for permitting motive fluid to act upon the exterior of said second gyratory member for causing said conjoint movement.

9. In a rock drill, a piston having a rearward extension of reduced diameter, a chuck formed for carrying a drill steel operated by said piston, a casing receiving said chuck and piston, said casing providing a wall with a bore for said rearward extension and a pair of annular chambers about said wall, gyratory members in said chambers, said gyratory members surrounding said wall and dividing said chambers each into a pair of sub-chambers, means associated with said casing and gyratory members for rendering one of said sub-chambers of each pair alternately expandible and contractable when said gyratory members operate, means permitting motive fluid to be admitted and exhausted to and from said sub-chambers so rendered for acting in each case directly upon a surface of the gyratory member and on an opposed surface of said casing for causing gyration of said member, and means for causing the gyrations of said members to rotate said chuck.

10. In a drilling machine, a chuck having external gear teeth, a gyratory member surrounding said chuck and having internal gear teeth meshing with the gear teeth on said chuck, a second gyratory member mounted rearwardly of said chuck, a casing for said chuck and both gyratory members, said casing providing an annular chamber having inner and outer walls, said second gyratory member being received in said annular chamber and surrounding said inner wall, means associated with one of said walls and said second gyratory member to form an expandible chamber, and means permitting

motive fluid to be admitted to and exhausted from said expansible chamber for acting directly upon one of said walls and a surface of said gyratory member opposed thereto for causing gyration of said member.

11. In a drilling machine, a chuck formed for carrying a drill steel, a hammer piston for operating said drill steel, said hammer piston having a head and a portion of reduced diameter, a casing in which said chuck and hammer piston are mounted, said casing being formed to provide an annular chamber rearwardly of said chuck about said portion of said hammer piston of reduced diameter, said annular chamber having inner and outer walls, a gyratory member received in said annular chamber and surrounding said inner wall, means cooperating with one of said walls of said annular chamber and the opposed wall of said member to form an expansible chamber, means for admitting motive fluid into said expansible chamber to act directly upon the opposed walls of said annular chamber and member and for exhausting said motive fluid therefrom, said admission and exhaust of motive fluid causing gyration of said member, and means for causing the gyration of said member to rotate said chuck.

12. In a drilling machine, a piston having a head and a rearward extension, a casing for said piston having a portion of large diameter for said head and a portion of smaller diameter for said rearward extension, a gear and a gyratory member surrounding said portion of smaller diameter, shafts, pinions on said shafts meshing with said gear, an eccentric on each shaft, said gyratory member being mounted on said eccentric, means permitting motive fluid to act upon the exterior of said gyratory member for gyrating it and rotating said shafts, a chuck, and a reduction gearing operatively connecting at least one of said shafts to said chuck.

13. In a drilling machine, a chuck, a motor for driving said chuck, said motor comprising a member mounted for gyration about the axis of said chuck, eccentrics at the sides of said axis supporting said member, means causing one eccentric to rotate when the other rotates, means permitting motive fluid to act on said member for gyrating it, a valve for controlling said motive fluid, a speed reducing connection between said member and chuck, and means causing said valve to move conjointly with said member.

14. In a drilling machine, a chuck, a motor for driving said chuck, said motor comprising a member mounted for gyration about the axis of said chuck on eccentrics at the sides of said axis, means permitting motive fluid to act on said member for gyrating it, a rotary valve for controlling said motive fluid, a speed reducing connec-

tion between said member and chuck, and means causing said valve to move conjointly with said member.

15. In a drilling machine, a chuck, a motor for driving said chuck, said motor comprising a gyratory member, axially spaced eccentrics upon which said gyratory member is mounted, a rotary valve for controlling the motive fluid for said motor, a pinion associated with each eccentric, and a common gear for connecting said pinions and rotating said valve.

16. In a drilling machine, a chuck, a motor for driving said chuck, said motor comprising a member mounted upon oppositely positioned eccentrics for gyration about the axis of said chuck, means causing one eccentric to rotate when the other rotates, and a rotary valve for controlling motive fluid for operating said gyratory member.

17. In a drilling machine, a drill steel, an impact motor for operating said drill steel, an independent motor coaxial with said drill steel for rotating said drill steel, speed reducing mechanism for transmitting the motion of said motor to said drill steel, a shaft parallel to the axis of said drill steel connecting said independent motor and speed reducing mechanism, and a valve for said independent motor driven by said shaft.

18. In a drilling machine, a chuck, a fluid pressure operated motor member mounted for gyration about the axis of said chuck on spaced eccentrics, a rotary valve for controlling the motive fluid for said gyratory member, and means including said eccentrics for converting the gyratory motion of said member to rotary motion and for imparting it to said chuck and to said valve.

19. In a drilling machine, a casing in which is mounted a pair of gyratory members, means forming with said casing and one of said gyratory members an expansible chamber, a chuck surrounded by another of said gyratory members, said chuck carrying external gear teeth in mesh with internal gear teeth carried by said gyratory member which surrounds said chuck, shafts carrying eccentrics for supporting both gyratory members, and the eccentrics supporting the gyratory member forming part of the expansible chamber having an eccentricity greater than those which support the gyratory member surrounding said chuck.

20. In a drilling machine, a motor comprising a fluid pressure operated member supported upon eccentric mechanism, a second member supported upon eccentric mechanism of lesser eccentricity, a chuck, and means causing said first mentioned member to drive the second mentioned and the second mentioned to drive the chuck.

21. In a drilling machine, a fluid pressure operated member supported for orbital movement, a second member supported for

orbital movement of smaller amplitude than the orbital movement of the first mentioned member, a chuck, and means causing said first mentioned member to drive said second mentioned member and the latter to drive said chuck.

22. In a drilling machine, a fluid pressure operated member supported for orbital movement, a second member supported for orbital movement of different amplitude from the orbital movement of the first mentioned member, a chuck, and means causing said first mentioned member to drive said second mentioned member and the latter to drive said chuck.

23. In a drilling machine, a chuck, a motor comprising a gyratory members, a second

gyratory member, a transmission between said gyratory member increasing the torque impressed upon said second member by said first member, and reduction gearing connecting said second member to said chuck.

24. In a drilling machine, a chuck, a chuck driving motor coaxial with said chuck, a gyratory gear member meshing with gear teeth on said chuck for driving the latter, and a transmission between said motor and gyratory member for increasing the torque impressed upon said gyratory member by said motor.

In testimony whereof, I have signed my name to this specification.

GEORGE H. GILMAN.

CERTIFICATE OF CORRECTION.

Patent No. 1,616,488.

Granted February 8, 1927, to

GEORGE H. GILMAN.

It is hereby certified that error appears in the printed specification of the above numbered patent requiring correction as follows: Page 6, line 17, claim 23, for the word "members" read "member" and line, 19, same claim, for the word "member" read "members"; and that the said Letters Patent should be read with these corrections therein that the same may conform to the record of the case in the Patent Office.

Signed and sealed this 22nd day of March, A. D. 1927.

Seal.

M. J. Moore,
Acting Commissioner of Patents.
